UNITED STATES PATENT OFFICE

111,682

DESIGN FOR AN ASHTRAY

John K. Milton, Chicago, Ill.

Application March 23, 1938, Serial No. 76,048

Term of patent 14 years

To all whom it may concern:

Be it known that I, John K. Milton, a citizen of the United States, residing at Chicago, in the county of Cook and State of Illinois, have invented a new, original, and ornamental Design for an Ashtray, of which the following is a specification, reference being had to the accompanying drawing, forming a part thereof, in which:—

Fig. 1 is a top plan view of the article showing my new design;

Fig. 2 is a front elevational view;

Fig. 3 is an end view from the left-hand side of Fig. 1.

I claim:—

The ornamental design for an ashtray, as shown.

JOHN K. MILTON.
